UNITED STATES PATENT OFFICE.

EDWARD A. PAGE, OF BERLIN HEIGHTS, OHIO.

BOX-FASTENER.

SPECIFICATION forming part of Letters Patent No. 633,896, dated September 26, 1899.

Application filed May 15, 1899. Serial No. 716,825. (No model.)

To all whom it may concern:

Be it known that I, EDWARD A. PAGE, a citizen of the United States, residing at Berlin Heights, in the county of Erie and State of Ohio, have invented certain new and useful Improvements in Box-Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improvement in box-fasteners. The object herein sought to be attained is to provide simple yet efficient means for holding and locking the covers of egg-crates and berry and other boxes when 20 closed and to prevent substitution or mixing of the covers by commission merchants and others when returning the empty crates or boxes; and it consists in the arrangement and combination of parts, which will be more fully 25 described hereinafter.

In the accompanying drawings, Figure 1 is a view in perspective of a box having a hinged cover and my fastener in service. Fig. 2 represents a vertical longitudinal section of the 30 same box. Fig. 3 is an end view of a portion of the box, showing the fastener locked in place. Fig. 4 represents a detail view of the fastener.

Similar letters and figures of reference when 35 they occur indicate corresponding parts in all views.

Referring to the drawings, A represents the box, which is preferably provided across one end thereof with a plain cleat a and across its 40 opposite end with a cleat a', having a vertical groove a².

B designates the cover, which is longer than the box, and to the under side of one of the projecting ends of said cover B is secured a plain cleat b, and to the under side of the opposite end thereof is fastened a cleat b', having a wide recess b² cut therein, as best shown in Figs. 1 and 3.

In Fig. 2 is shown one way of hinging the 50 cover B to the box A, the hinges C being secured by screws or equivalent device to the plain cleats b and a. This hinging is done to

prevent substitution of the covers by commission merchants and others when returning the "empties," an annoyance quite universal. 55

The fastener D consists, preferably, of a piece of suitable spring-wire, which is first doubled upon itself and then arranged and treated to form a curved handle portion 1, a pair of oppositely-disposed shoulder or holding portions 2, parallel shank portions 3, two coiled portions 4, and end portions or terminals 5, and in order that the tips X of these end portions 5 may be rendered less brittle and be more easily clenched or bent when desired 60 to hold the said fastener D tightly in place, substantially as indicated by the dotted lines seen in Fig. 3, I anneal them. In the under side of cleat a' on each side of its vertical groove a² is driven a small staple E to serve 65 as catches or stops for the spring-fastener D, as is evident and plainly seen in Figs. 2 and 3 of the drawings.

The top portions 5 of the spring-fastener D are inserted in holes F, formed in the cleat b', 75 and so fastened therein that the coils 4 of said fastener D will snugly lie in the wide recess b² thereof and be protected from injury thereby. It is also evident that the vertical groove a² will accommodate the shanks 3 of 80 the said fastener D.

The box may be readily opened by pulling the handle portion 1 slightly outward and then raising the cover, and when properly arranged and adjusted the said fastener E is 85 self-locking when the cover is depressed.

If a removable cover is desired, the hinges C and their cleats may be dispensed with and the fastener D and its cleats a' and b' substituted therefor and used in lieu thereof. 90

It is my intention to manufacture cleat b', carrying fastener D, and cleat a', carrying staples E, in quantities for the trade, to be applied to suitable boxes by the users.

I do not wish to be understood as confining 95 myself to the exact construction herein shown, as the device may be made in a number of ways without departing from the spirit and purpose of my invention.

Having thus described my invention, what 100 I claim, and desire to secure by Letters Patent, is—

In a box-fastener, a box provided with a cleat upon one end, and which cleat is pro-

vided with a vertical groove through which the shank of the fastener extends, and a cleat upon the end of the cover having a recess formed in its lower edge above the groove in 5 the cleat upon the box, combined with a spring-fastener formed from a single piece of wire having a head upon its lower end, a shank which extends through the groove in the cleat on the box, a spring formed near 10 the upper end of the wire and having annealed points or tips which are forced through the cleat on the cover; the spring portion of

the fastener being located in the recess in the lower edge of the cleat upon the cover; and the staples behind which the head of the 15 spring catches, substantially as shown and described.

In testimony whereof I affix my signature in presence of two witnesses.

EDWARD A. PAGE.
